UNITED STATES PATENT OFFICE

92,146

DESIGN FOR A DISPLAY DEVICE

Harry Lazarus, Chicago, Ill.

Application February 12, 1934, Serial No. 50,689

Term of patent 3½ years

To all whom it may concern:

Be it known that I, HARRY LAZARUS, citizen of the United States, and residing at Chicago, county of Cook, and State of Illinois, have invented a new, original, and ornamental Design for a Display Device, of which the following is a specification, reference being had to the accompanying drawing, forming a part thereof.

The drawing is a perspective view of the display device, showing my new design.

I claim:

The ornamental design for a display device as shown.

In witness whereof I affix my signature.

HARRY LAZARUS.
